G. LISSAC

Des. 168,515

PAIR OF SPECTACLES

Filed Feb. 4, 1952

UNITED STATES PATENT OFFICE

168,515

PAIR OF SPECTACLES

Georges Lissac, Paris, France

Application February 4, 1952, Serial No. 18,363
In France August 8, 1951

Term of patent 14 years

(Cl. D57—1)

To all whom it may concern:

Be it known that I, Georges Lissac, a citizen of the Republic of France, residing at Paris, France, and having a post office address at 112-114 rue de Rivoli, Paris, France, have invented a new, original, and ornamental Design for Pair of Spectacles, of which the following is a specification, reference being had to the accompanying drawings, forming part thereof.

Fig. 1 is a front elevational view of a pair of spectacles showing my new design;

Fig. 2 is a top plan view thereof;

Fig. 3 is a rear elevational view; and

Fig. 4 is a side elevational view.

I claim:

The ornamental design for a pair of spectacles, as shown.

GEORGES LISSAC.
